FLUSHING APPARATUS

William J. Dunn, Lake Charles, La.

Application September 1, 1943, Serial No. 500,857

7 Claims. (Cl. 134—169)

This invention relates to means for flushing the radiators of automotive vehicles and the like. A main object of the invention is to provide means whereby an improved flushing action is obtained by imparting a surging or agitating effect to the flushing fluid while the latter is in flow through the radiator and without the necessity of dismounting the radiator. How this object may be obtained will be described with reference to the accompanying drawing in which:

Figure 1 shows in elevation a radiator in process of flushing in accordance with the invention;

Figure 2 is an axial section on an enlarged scale of a flushing device which appears in Figure 1;

Figure 3 shows the device of Figure 2 partly in section and partly in elevation in a different relation of parts; and

Figure 4 is a section substantially on line 4—4 of Figure 3.

In Figure 1, reference numeral 10 designates generally a radiator of conventional type including a top filling neck 11 and top and bottom connections 12 and 13 through which the radiator is normally connected into the circulatory system which includes the engine jacket. The hose sections which normally connect the radiator connections and the engine are removed in Figure 1, the top connection is closed as by a plug 14, and the bottom connection has associated therewith a flushing device 15 in accordance with the invention.

This device comprises an inner tubular portion 16 which can be of any suitable material. Conveniently, it may be constituted by a section of radiator hose adapted to have its inner end 17 slipped over the connection 13 to form a fluid-tight joint therewith, and a clamp 18 may be provided. Or, any suitable adapter may be provided between the radiator connection and portion 16, as when the latter is of rigid material. Just outwardly of its end 17 portion 16 has connected into it a hollow L-shaped fitting 18 whose branch portion 19 is equipped with a swivelled hose connector 20. Working in the cylindrical portion 21 of the fitting is a valve 22 carried on a stem 23 which is threaded in an end bushing 24. In the position shown in Figure 3 the valve 22 blocks the portion 21 in advance of the branch 19, but by threading the stem outwardly the branch can be fully freed for flow. Toward its outer end portion 16 is provided with lateral openings 25.

Embracing the inner tubular member 16 is an outer tubular member 26 which may also be a

section of radiator hose, there being a substantial flow clearance 27 between the two portions. The outer end of portion 26 has fixed thereto a closure cap 28 which carries a piston 29 by means of a rod 30, the piston being adjacent the inner end 31 of the outer portion and being substantially smaller than the inner diameter of the inner portion so that a substantial flow clearance 29' is present between the two.

With the device 15 applied to the lower hose connection 13 in the manner shown in Figure 1 and valve 22 in the position shown in Figure 3, water is continuously run into the filling neck 11 from a hose 32. The plunger constituted by the outer portion 26 and the piston 29, or either of them, is now reciprocated, but without such an extent of outward movement as to cause the openings 25 to be uncovered by the outer portion 26. During this time outflow from the radiator continues between the piston 29 and portion 16 and between the latter and portion 26 although the plunger means imparts a surging or agitating effect to the liquid flowing through the radiator with the result that accretions are loosened and carried downward by the flow. After several reciprocations, portion 26 is moved outwardly sufficient to uncover openings 25, permitting the radiator to drain more freely for a period. Splash from the openings 25 is restrained by a tubular guard 33 fixed around the inner end of portion 26. The reciprocating and drainage actions are repeated as many times as necessary.

Under some conditions the cleaning operation can be facilitated by introducing flushing fluid through the lower hose connection, and in this case the hose 32 is engaged with the fitting 18 through the coupling 20 and valve 22 is retracted so as to permit free flow to the interior of portion 16, portion 26 being held substantially in the relation shown in Figure 2. This will usually loosen a badly clogged radiator and thereafter the hose is transferred to the filling opening and the agitator used as above described.

The purpose of plugging the upper hose connection is, of course, to prevent wasting of the flushing fluid through the engine jacket and this result, of course, can be secured otherwise. For example, the upper connection can be pinched, or the lower radiator hose can be pinched or plugged after detachment from connection 13 so as to prevent flow through the engine jacket. Or the radiator cap can be left in place and the flushing hose slipped over the top connection.

The invention is, of course, not limited to the procedure and apparatus which have been de-

scribed by way of example, but contemplates all variations coming within the following claims.

I claim:

1. A device for use in flushing a radiator having a top opening for a flushing fluid and having a bottom connection, said device comprising an inner tubular portion engageable with said connection, said tubular portion being open from end to end for flow of the flushing fluid therethrough, and an outer tubular portion reciprocable over said inner portion with flow clearance between the two portions, and means closing the outer end of said outer portion, the flow clearance between said tubular portions being in communication with the inner tubular portion at the end thereof adjacent the closing means for escape of the flushing fluid through said clearance.

2. A device for use in flushing a radiator having a top opening for a flushing fluid and having a bottom connection, said device comprising an inner tubular portion engageable with said connection, said tubular portion being open from end to end for flow of the flushing fluid therethrough, and an outer tubular portion reciprocable over said inner portion with flow clearance between the two portions, and means closing the outer end of said outer portion, the flow clearance between said tubular portions being in communication with the inner tubular portion at the end of the latter adjacent the closing means for escape of the flushing fluid through said clearance, said inner portion having a lateral escape opening outwardly of the normal reciprocating range of said outer portion.

3. A device for use in flushing a radiator having a top opening for a flushing fluid and having a bottom connection, said device comprising an inner tubular portion engageable with said connection, said tubular portion being open from end to end for flow of the flushing fluid therethrough, and an outer tubular portion reciprocable over said inner portion with flow clearance between the two portions, means closing the outer end of said outer portion, the flow clearance between said tubular portions being in communication with the inner tubular portion at the end of the latter adjacent the closing means for escape of the flushing fluid through said clearance, and a valve-controlled hose connection into said inner portion inwardly of the normal reciprocating range of said outer portion.

4. A device for use in flushing a radiator having a top opening for a flushing fluid and having a bottom connection, said device comprising an inner open-ended tubular portion engageable with said connection, and an outer tubular portion reciprocable over said inner portion with flow clearance between the two portions, means closing the outer end of said outer portion, and a piston carried by said outer portion and working in said inner portion with flow clearance between it and said inner portion.

5. A device for use in flushing a radiator having a top opening for a flushing fluid and having a bottom connection, said device comprising an inner open-ended tubular portion engageable with said connection, and an outer tubular portion reciprocable over said inner portion with flow clearance between the two portions, means closing the outer end of said outer portion, and a piston carried by said outer portion and working in said inner portion with flow clearance between it and said inner portion, said piston being adjacent the inner end of said outer portion.

6. A device for use in flushing a radiator having a top opening for a flushing fluid and having a bottom connection, said device comprising an inner open-ended tubular portion engageable with said connection, and an outer tubular portion reciprocable over said inner portion with flow clearance between the two portions, means closing the outer end of said outer portion, said inner portion having a lateral escape opening outwardly of the normal reciprocating range of said outer portion, and a piston carried by said outer portion and working in said inner portion with flow clearance between it and said inner portion, said piston being adjacent the inner end of said outer portion.

7. A device for use in flushing a radiator having a top opening for a flushing fluid and having a bottom connection, said device comprising an inner tubular portion engageable with said connection, an outer tubular portion surrounding said inner portion with flow clearance between the two portions, means closing the outer end of said outer portion, a lateral opening in said inner portion connecting the interior of said inner portion with said clearance, and a piston in said inner portion reciprocable past said lateral opening.

WILLIAM J. DUNN.
